[57] **CLAIM**

The ornamental design for a combined pegboard and console for a van, as shown and described.

DESCRIPTION

FIG. 1 is a top perspective view of a combined pegboard and console for a van showing our new design; FIG. 2 is a left sideelevational view thereof;

FIG. 3 is a top plan view thereof;

FIG. 4 is a rear elevational view thereof; and,

FIG. 5 is a front elevational view thereof.

The broken lines shown in FIGS. 2, 4 and 5 representing pegs are for illustrative purposes only and form no part of the claimed design.

FIG. 2

FIG. 1

FIG. 3

FIG. 4

FIG. 5
